UNITED STATES PATENT OFFICE.

BERT N. PARRISH, OF JACKSON, MICHIGAN.

QUADRUPLE-RELAY CROSSING-SIGNAL.

SPECIFICATION forming part of Letters Patent No. 688,964, dated December 17, 1901.

Application filed August 1, 1900. Serial No. 25,546. (No model.)

To all whom it may concern:

Be it known that I, BERT N. PARRISH, a citizen of the United States, and a resident of Jackson, in the county of Jackson, State of Michigan, have invented a new and useful Quadruple-Relay Crossing-Signal, of which the following is a specification.

The object of this invention is to employ in a signaling system a signal, either a bell or a semaphore, and two sets of relays located in endwise reverse order to each other at the crossing, each set consisting of a signal-circuit-reversing relay with normally open circuit and a track-circuit relay with a normally closed circuit, whereby in case trains were running close together and an incoming train or car should approach the crossing within the signaling radius before the outgoing train or car had advanced beyond the signaling radius said incoming car or train would give the warning-signal the same as the first incoming car (now outgoing) gave said signal.

In the drawings forming a part of this specification, Figure 1 is a diagrammatical view showing the system; Fig. 2, a side elevation of relays 4 and 5 in Fig. 1 with their arms 14 and 15, and Fig. 3 shows broken details of the signaling maker and breaker in Fig. 2 and below described.

Referring to the parts of the drawings pointed out by numerals, 4 represents the electromagnets of the track-circuit relays, and 5 the electromagnets of the signal-circuit relays. I term them "sets of double relays." One set is for all purposes of effect and description considered as being on one side of the crossing and the other set on the other side of said crossing.

At 7 is the bell, or if a semaphore were used it would be located here or somewhere near the crossing. The regular line of rails of the main track are shown broken at 8. In the line of the track-rails 8 are two short block-sections 13 and an intermediate shorter block-section 12 at the crossing. In the rail opposite is a long block-section 10 at the crossing and extending out each way, as do also the block-sections 13, from the crossing a sufficient distance.

The signal maker and breaker in Fig. 2 consists of the horizontal armature-arm 15 and relay 5 and the upright armature-arm 14, with

its contact-plate 17 and its insulating-cap 16. The end of the arm 15 is bent down at 18 in position to contact with the contact-plate 17 and the insulating-cap 16 when the armature-arm 14 operates, as explained farther on.

The block-sections 10 and 13 are connected at both sides of the crossing by batteries 22 and wires 20 and 21.

The circuits are traced in connection with a description of the operation.

The right and left hand track-circuits are traced, beginning with batteries 22, over wires 21, block-sections 10, wires 26, relays 4, wires 65 25, block-sections 13, and wires 20. These circuits energize the magnets 4, normally holding their armature-arms 14 in an upright position, as in Fig. 2, and in contact with the magnets, thus closing the track-circuits. 70 Shunting-circuits are established by the presence of the wheels of a car on the block-sections 10 and 13 and are traced from batteries 22 over wires 20, block-sections 13, wheels and axle of car, block-section 10, and wires 75 21. When a car is in this position at one side of the crossing, the track-circuit at said side is short-circuited by robbing said track-circuit of electric power from a battery 22, thus deenergizing magnet 4 at said side. 80

The open signal-circuits are traced from battery 24, wire 28, signal 7, wires 31 27, contact-plate 17, armature-arms 15, and wires 30 and 32. When the magnets of the relays 4 are deenergized as and by the cause above 85 stated, the armature-arms 14 swing over, as shown by dotted lines in Fig. 2, bringing the contact-plates 17 against the ends 18 of the armature-arms 15, making the signal-circuit and giving the signal, warning the people at 90 the crossing of an approaching car.

The local cut-off circuits are traced from the battery 23, wires 35 33, relays 5, wires 34 26, block-section 10, wheels and axle of car, and wire 35. When an incoming car arrives 95 at the crossing, with its front wheels on the block-sections 10 and 12, the signal stops, because the relays 5 become energized, raising arm 15 to the dotted position in Fig. 2 and disconnecting the end 18 of armature-arm 15 100 from the contact-plate 17 of arm 14. When an incoming car has left the block-section 13 in its rear, the relay 4 in its rear becomes again energized, bringing its armature-arm

14 up to its normal position again. When the forward wheels of an outgoing car make the block-sections 10 and 13, the circuit between the block-sections 10 and 12 being still 5 closed by the rear wheels and axle of the car, the power of the battery 22 forward of the car is shunted, deenergizing the magnets of the relay 4 forward of the car, allowing the armature-arm 14 of said relay to fall back 10 under the end 18 of armature-arm 15, and when the outgoing car has passed entirely off from block-section 12 the relays 5 are deenergized, allowing the armature-arm 15 in front of the car to rest on the insulating-cap 15 16, as in Fig. 3, and thus provision is made for the outgoing car not to give the signal. At the same time the armature-arm 15 in the rear of the car is lowered to its normal position. The construction and operation set 20 forth just above permit the signal being given by an incoming car from the same direction in which the now outgoing car came, while said outgoing car is still on section 13, thus avoiding danger in cases where one train 25 or car closely follows another. When the outgoing car has cleared the block-sections 10 and 13, the armature-arms 14 and 15 immediately in its rear will be set again to their normal position.

30 The operation of the sets of relays and the circuits are of course the same, matters not from which way the car approaches or which way it goes out.

Having thus described my invention, what 35 I claim as new, and desire to secure by Letters Patent of the United States, is—

In a railway-crossing signal, two sets of double relays, one set each side of the crossing, said sets of relays consisting each of an 40 electromagnet in normally closed circuit with a short block-section in one rail of the track at its respective side of the crossing and a long block-section in the other rail of the

track, said electromagnets each holding a pivoted armature provided with an insulating- 45 cap, and a spring for drawing it from the magnet when released, each of said armatures constituting one terminal of an open relay signal-circuit; and each of said sets of relays further consisting of a second electromagnet 50 provided with a pivoted armature each constituting the other terminal of an open relay signal-circuit, said second electromagnets being each in open circuit with the above-mentioned long block-section and an intermediate 55 block-section located at the crossing between the two short block-sections, two normally open relay signal-circuits common to the signal and common to both sets of the double relays, each adapted to be closed by contact 60 of the armature having the insulation-cap with the end of the other armature when the presence of an incoming car in proper section short-circuits the normally closed track-circuit and adapted to be opened again when 65 the car closes the circuit of the said second electromagnet raising both of their armatures, the construction and arrangement being such that when the outgoing car has passed intermediate block-section the armatures of the double relay in the rear of the car are set to their normal position, while the armatures of the other double relay are prevented by the interposition of the aforesaid insulating-cap from contacting to close the 70 signal-circuit and are only reset when the outgoing car has passed all the block-sections 75 substantially as set forth.

In testimony of the foregoing I have hereunto set my hand in the presence of two witnesses.

BERT N. PARRISH.
